DECK PUMP

Arthur C. Anderson, Wildwood, N. J.

Application January 28, 1947, Serial No. 724,831

4 Claims. (Cl. 114—184)

1

My present invention relates to pumps, and more particularly to a bilge pump adapted to be installed in the deck of a boat with the upper surface of the pump cover lying flush with the deck.

The general object of my invention is to provide a simple, compact, and reliable pump, easy to install and repair and which will replace the present deck pump which is usually mounted on top of the deck, or on a floor, and hence constitutes an obstacle over which to stumble as well as being exposed to freezing in sub-zero weather.

Other objects and novel features of the construction and arrangement of parts comprising my improved pump will appear as the description of the invention progresses.

In the accompanying drawings illustrating a preferred embodiment of my invention:

Figure 1 is a sectional side elevation of my improved pump shown installed flush with the deck of a boat or similar structure.

Figure 2 is a plan section on the line 2—2 of Fig. 1 and looking in the direction of the arrows.

Figure 3 is a sectional end elevation, taken on the line 3—3 of Fig. 1, and looking in the direction of the arrows, and

Figure 4 is a sectional plan view taken on the line 4—4 of Fig. 3, and looking in the direction of the arrows.

My novel pump is characterized in the following respects: By being housed in the deck, rather than above deck, the entire deck space is available and a hazard to traffic eliminated. Dangerous conditions around the pump, due to water coming inboard from the sea and freezing, or oil and dirt from the bilge water flushing over the deck are eliminated. Both the suction and the discharge pipes are installed below deck and the pipe connections to the discharge port are located at the bottom of the pump. This makes it easier to pipe up the pump in installations where beams or the like would ordinarily interfere with the piping. The pump cover acts as a rocker arm for operating the pump piston and is thus a part of the operating mechanism of the pump which will never be omitted or forgotten. When the pump is not in use and the operating handle removed, the cover is left in place flush with the deck, and hence will automatically drain itself. Moreover, the cover, the link which connects the cover to the piston, and the piston itself may all be removed as a unit without removing any bolts, nuts or pins. This

5 eliminates the need for tools when priming, draining or cleaning the several valves of the pump. The drain valve is automatic and can be easily removed when not needed. It drains both the suction and the discharge chambers, which is an advantage when the pump is used in freezing weather. Also the piston and the discharge port outlet are so designed as to provide a longer guide and a better seal for the piston. Other advantages will appear from the following detailed description of the construction and operation of my pump.

Referring to the drawings, 10 designates the deck of the boat, or the floor of a loft or other structure, provided with an orifice 11 through which extends a pump body 12 having attached thereto or formed integral therewith an annular plate 13, the upper surface of which lies flush with the deck 10. Associated with the annular plate 13 is a pivoted cover plate 14, which, when closed, lies flush with the annular plate 13 and deck 10.

20 The cover plate 14 is pivotally mounted on a shaft 15 rotatably mounted in spaced ears or lugs 16 on the under face of the annular plate 13.

25 The spaced ears or lugs 16 are provided with slots through which may pass the non-cylindrical ends of the shaft 15. With this construction, the cover plate 14 may be inserted in position in the spaced ears or lugs 16 or removed therefrom at will, without the necessity of removing bolts, nuts, or other fastening means. Further, all parts attached to the under face of the cover plate 14, as hereinafter described, may be removed as a unit for inspection, repair or cleaning.

30 On the under face of the cover 14 is a rib 17 having a socket 18 formed therein and with the upper end thereof terminating in a slot (not shown) in the cover plate 14. The socket 18 receives a handle 18a by means of which the cover plate 14 may be oscillated between the full line position, and the dot and dash line position shown in Fig. 1 to operate the pump piston.

35 Formed within the pump body 12 is a cylinder 19 having its bottom 20 spaced apart from the bottom of the body as shown. A vertical web 21 extends across the pump body 12 between the bottom 20 of the cylinder 19 and the bottom of the pump body 12, (see Fig. 1) thus dividing the pump body into two chambers, an intake chamber 22 and a discharge chamber 23.

40 Connecting with the intake chamber 22 is an intake port 24 having a pipe 24a connected

thereto and leading to the bilge of the boat. Connecting to the discharge chamber 23 is a discharge port 25 having a pipe 25a connected thereto and leading outward through the side of the boat at a point above the water line.

In the bottom 20 of cylinder 19 and within the confines of the intake chamber 22 are intake ports 26 provided with an intake valve leather 27 having secured thereto a valve weight 28, the valve leather being secured to the bottom 20 by the bolts 29 and clamps 29a. Also, for one of the bolts 29 there has been substituted a discharge valve stop stud 51 (see Fig. 3) and which is in alignment with one of the piston intake valve leathers 39. The function of the discharge valve stop stud 51 is to engage with the valve leather 39 to open the piston intake ports 38 and permit water to pass above the piston head and into the outlet chamber 23.

In the bottom 20, within the confines of the discharge chamber 23, is the discharge chamber valve comprising a drain cage 30 screwed into the bottom 20, said cage having a valve seat 31, and a plurality of drain passages 32a extending from the seat 31 into the chamber 23. Slidably mounted in the cage 30 is a sliding valve 32 on the stem of which is mounted and secured by nut 33 a coil spring 34 which constantly urges the valve 32 into closing engagement with the valve seat 31.

Mounted within the cylinder 19 for reciprocating movement therein by cover 14 and its handle is a piston 35, the skirt 36 of which is provided at one side with an open port 37 (see Fig. 1). The head of the piston 35 is provided with a plurality of piston intake ports 38 normally closed by the piston valve leather 39, such leather being weighted by valve weights 40 held on the leather by the rivets 41. The members 39, 40 and 41 are secured to the head of the piston 35 by a connecting link bracket 42 and bolts 43. Pivots connected to a bearing pin 44 rotatably mounted in the central upper end of the connecting bracket 42 are the lower ends of the connecting links 45, the upper ends of which are pivotally mounted on a bearing pin 46 which is rotatably mounted in the rib 17 on the under face of the cover plate 14.

With the device constructed and arranged as above described, the normal or inoperative position of the parts relative to each other is as shown in full lines. The intake pipe 24a leads to the bilge of the boat in which the device is installed. The discharge pipe 25a leads out through the side of the boat at a point above the waterline. The intake port valve leather 27 closes the intake ports 26. The discharge valve 32 is held open by the piston. The piston 35 is in its lowermost position with its valve leathers 39 closing the piston intake ports 38.

The operator places the lever 18a in the socket 16 and swings the upper end thereof to the left, as viewed in Fig. 1, and as shown in broken lines, thereby swinging the cover plate 14 in an arc about the shaft 15, and, by means of the connecting links 45, drawing the piston 35 upwardly in the cylinder 19 to the dot and dash line position shown in Fig. 1.

Immediately upon the start of this upward movement of the piston 35, the valve 32 seats on the valve seat 31, thus closing the chamber between the piston and the cylinder head; the intake valve leather 27 opens the inlet ports 26 and suction is created in the intake pipe 24a, thereby drawing the water upward through the pipe 24a and filling not only the intake chamber 22 but

allowing the water to flow upwardly through the inlet ports 26 and into the chamber between the piston and cylinder head. Should the pump require priming, this may be easily done by pouring water into the upper end of the piston 35.

The handle 18a having reached the dot and dash line position is now moved back to its starting position, as shown in full lines in Fig. 1. During this movement the valve leather 27 seats on the intake ports 26, while the valve leathers 39 lift away from the piston intake ports 38 in the cylinder head, forcing the water upwardly and into the piston 35. As the piston moves upwardly, the water within such piston flows through the discharge port 37 of the piston into the discharge chamber 23, and from thence through the discharge pipe 25a outward through the side of the boat.

After the pumping operations have been completed, the operator moves the handle 18a to the full line position shown in Fig. 1, bringing the piston head into engagement with the discharge valve 32, thus depressing the valve and permitting the water in the chamber between the piston and cylinder to flow downwardly into the discharge pipe 25a, and simultaneously opening one of the ports 38 to permit water in the body of the piston 35 to flow downwardly and through the valve 32 into the discharge pipe 25a.

The pumping operation having been completed and the pump drained, the operator removes the handle 18a from the socket 16.

It will be noted that all parts of my pump are readily accessible without the necessity of removing any bolts, nuts, or pins; that the pump is made with a minimum number of parts; and that these parts are so designed and arranged as not to corrode or depreciate through long use. My pump is self-draining, and easy to prime.

It displaces the maximum amount of water with the minimum of effort, and is so designed as to give long reliable service.

It is flush with the deck and is protected from freezing, by being housed from the weather. It adds measurably to the safety of all on board the boat, as it cannot be stumbled over, is not injured by seas coming over the deck, and is always ready for instant use.

Further, if it is desired to remove the piston or other parts of the pump connected to the cover plate 14, this may be accomplished by merely swinging such cover plate 14 upwardly and to the left, as viewed in Fig. 1, until the non-cylindrical ends of the shaft 15 come into registry with the slots in the ears or lugs 16, whereupon the cover plate 14, links 45, piston 35, and all parts attached thereto may be lifted from the pump as a unit.

Obviously various changes in the size, shape and arrangement of parts may be made by those skilled in the art, and I am therefore not to be limited to the exact construction shown and described other than as required by the appended claims.

Having thus described my invention, what I claim as new and desire to secure by Letters Patent is:

1. An improved deck pump comprising, a casting having formed therein a cylinder, intake chamber and discharge chamber, means for connecting the intake chamber to the bilge of a boat or the like, means connecting the discharge chamber to the side of a boat at a point above the water line, means including a deck engaging flange on and extending outwardly from the top

margin of the casing for positioning the casing beneath the deck of a boat, a cover plate hinged to the casing and in closed position being flush with the flange and the deck of the boat, a piston mounted for reciprocation in said cylinder, a discharge port formed in one wall of said piston, an intake valve positioned between the intake chamber and cylinder, valves in the bottom wall of the piston to receive water from the intake chamber and deliver the same through the discharge port to the discharge chamber, and means for reciprocating the piston in the cylinder.

2. An improved deck pump comprising a casing having formed therein a cylinder, intake chamber and discharge chamber, means including valves connecting the intake chamber to the interior of the cylinder, a piston having bottom and side walls and mounted for reciprocation in the cylinder and having valves mounted in the bottom wall and connecting the interior of the piston with the cylinder, a deck engaging flange carried by and extending laterally outward from the top margin of the casing for supporting the casing therebeneath and beneath the deck of a boat, a cover plate hinged to the casing and in closed position being flush with the flange and the deck of the boat, link connections between the cover plate and piston, means including a handle for oscillating the hinged cover plate to impart reciprocating movement to the piston, a discharge port formed in the piston, and operable to discharge water passed into the piston through the valves in the head of the piston, from a chamber formed between the bottom of the cylinder and the head of the piston.

3. The deck pump defined in claim 2 plus a drain valve disposed in the bottom wall of the

cylinder beneath the piston, and means normally holding the valve closed, the piston acting to open the valve when the piston is in its lowermost position.

5. A deck pump comprising a casing having an open top end, said casing including integral exterior and interior walls forming within the casing a cylinder, an intake chamber beneath the cylinder, and a discharge chamber located laterally with respect to the cylinder, deck engaging means at and extending outwardly from the top margin of the casing for resting on a deck and supporting the casing suspended therebeneath, a piston in the cylinder, a cover plate pivoted to the casing in position to cover said open end, a link connecting the cover plate with the piston, means including ports and valves for drawing water into and discharging it from the casing when the piston is reciprocated, and means including a removable handle associated with the cover plate for oscillating it about its pivotal connection to the casing.
